UNITED STATES PATENT OFFICE.

PETER NYHOLM, OF EDGEWOOD, WASHINGTON.

EXTENSION-TABLE.

1,337,092.

Specification of Letters Patent. Patented Apr. 13, 1920.

Application filed August 23, 1919. Serial No. 319,398.

To all whom it may concern:

Be it known that I, PETER NYHOLM, a citizen of the United States, residing at Edgewood, in the county of Pierce and State of Washington, have invented certain new and useful Improvements in Extension-Tables, of which the following is a specification.

My invention relates to extension tables and has for its primary object to provide 10 folding filler leaves for such tables which may be stored beneath the permanent table top sections, whereby they are in convenient position for use when the table is extended.

The further object of my invention is 15 to provide folding filler leaves with coöperating attachments whereby they may be applied to any ordinary extension table.

My invention consists in the various novel parts and combination of parts as will be 20 hereinafter more fully pointed out.

In the drawing Figure 1 is a top plan view of an extension table top with my improved filler leaves in place and in extended position.

Fig. 2 is a similar view with some of the leaves in stored position and one leaf in semi extended position.

Fig. 3 is a vertical sectional view looking in the direction of the arrow on the line 30 3—3 Fig. 2.

Fig. 4 is a detailed sectional view, looking in the direction of the arrow on the line 4—4 Fig. 2.

Fig. 5 is an enlarged detailed view of a 35 filler leaf, in extended position, and broken away.

Fig. 6 is an end elevation of a filler leaf in closed position and broken away.

Figs. 7 and 8 are detailed vertical views 40 of a center pedestal table showing my invention applied.

The reference numerals 1 and 2 designate the permanent table top sections of an extension table of any approved construction, said table being provided with the usual extension slides 3 and 4, the slides 4 being secured to the permanent sections 1 and 2 as shown in Fig. 2.

Beneath the slides I position a suitable 50 support 5 which, in effect, constitutes the base upon which the filler leaves are mounted, said support may be secured to the center leg 6' of the table in any suitable manner.

On the support 5 I position suitable journal bearing blocks 6 in series, the number

being dependent upon the number of filler leaves employed in said blocks and journal rod 7 which rod may be common to all of the filler leaves. To one side of the journal or rod 7 I secure center guides 8 to the journal bearing blocks 6, said guides being inclined toward the center of the space between said blocks as clearly shown in Fig. 7.

A link 9 is loosely journaled, at its lower end, on the rod 7 between a pair of the journal blocks 6 whereby the link is free to swing to both sides of the rod 7, as in the position shown in Fig. 3 and to the position shown in Fig. 4 to facilitate the storing and the extension of the folding filler leaves 10. The sections of the folding filler leaves are connected together by means of a suitable hinge which hinge, in the illustration shown, comprises two members 11 the abutting ends of each of which are provided with a recess 12 in which a link 13 is mounted, said link being suitably secured to the respective hinge members by means of the pivots 14, whereby the sections of the filler leaves may be moved into and out of folded and extended position without binding at the abutting edges of the sections of the leaf. One of the sections of the leaf is provided with a projecting support 15 abridging the joint between the two sections of the leaf, thereby relieving the hinge of any undue strain or tension as will be understood by those skilled in this art.

Each folding filler leaf is provided with journal bearing blocks 16, arranged in pairs between which extend a rod 17' which passes through said blocks and also passes loosely through the upper end of the link 9 whereby the link 9 has a loose pivotal connection with the filler leaf.

In order to limit the downward movement of the link 9 on one side of the rod 7 I provide a stop 17 having an inclined upper face the angle of which is predetermined so that the link 9 engages the stop 17 when the filler leaf has reached the position of the top plane of the permanent table top as shown in Fig. 4. This stop 100 not only limits the downward movement of the link 9, as above described, but it also serves as a support between its journal rod 7 and its connection 17 with the filler leaf to support inner end of the leaf section in 110 its elevated position as shown in Fig. 4. In order to further support the filler leaf at

its center joint against downward movement when in extended position I secure to the under side of one section of the filler leaf a stop 18 the under face of which is 5 formed on an angle which insures a snug contact fit with the upper surface of the link 9 as clearly shown in Fig. 4. A strip 19 is secured on the support 5 upon which rests the free ends of the folding leaf as 10 illustrated in Fig. 3.

When my attachment is used in connection with a split center pedestal the support 5 is secured to the center leg 20 whereby the sections 21 of the split pedestal are free to 15 move with the permanent sections of the table top.

From the above it will be seen that to place the filler in operative extended position it is only necessary to grasp the leaf 20 desired and with the upward movement swing the leaf on its link 9 thereby moving the folding leaf to proper position to be extended whereupon the uppermost section of the leaf is moved over on its hinge connection so that the leaf is presented in its 25 extended position level with the upper face of the permanent table top sections. There is no additional movement or adjustment of any parts necessary to secure the filler leaf in its proper extended position and the stops and links rigidly hold the filler leaf against endwise movement as well as against collapsing downwardly at its hinged joint, so that the filler leaves are just as rigid in their 30 extended position as are the permanent table top sections.

If desired the filler leaves may be provided with the usual pegs and peg sockets and when so provided the link is made relatively narrow whereby it has a greater freedom of sidewise movement between its journal blocks 6 to accommodate the movement necessary in inserting the pegs into the peg 40 openings of adjacent leaves.

45 What I claim is:—

1. In an extension table the combination with the table top structure having a compartment for storing extra table leaves, of a link pivotally mounted at its lower end 50 within said compartment and adapted to swing to both sides of its pivotal connection, a folding table leaf pivotally connected to the upper end of said link, and a stop carried by said leaf and adapted to engage said link to hold the leaf in the plane in the top of the table.

2. In an extension table, the combination with the table top structure having a compartment for the storage of extra table 60 leaves, of a link pivotally connected at its lower end within said compartment adapted

to swing to both sides of its pivotal connection, means in said compartment to limit the downward movement of said link on one side of its pivotal connection, a folding table leaf pivotally mounted on the upper end of said link, and means on the under face of said table leaf adapted to engage the link said means coöperating with the first mentioned means to limit the downward movement of said link on one side of its pivotal connection.

3. In an extension table, the combination with the table top structure having a compartment for the storage of extra table leaves, of bearings within said compartment, a rod mounted in said bearings, a link pivotally mounted at its lower end on said rod and free to swing to either side of said rod, a folding table leaf pivotally mounted 80 on the upper end of said link, a stop in said compartment, and a stop on the under face of said table leaf, both stops engaging said link to limit the downward movement of the link on one side of its pivotal connection. 85

4. In an extension table, the combination with the table top structure, journal bearings secured to said structure and a journal extending between said bearings, a link pivotally mounted at its lower end on said journal; a folding table leaf pivotally mounted on the upper end of said link, said link being capable of moving to both sides of its lower pivotal connection, stops mounted on the table structure and on the folding table leaf 90 adapted to engage the link and coöperating to limit the downward movement of the link on one side of its journal, whereby the leaf may be swung in folded condition below the level of the top of the table and whereby it 100 may be moved on said link to the plane of the top of the table, said link being adapted to slide sidewise on its journal, and guides to one side of said journal adapted to center the link between its journal bearings when 105 the table top is in stored position.

5. In an extension table the combination with the table top structure having a compartment for storing extra table leaves, of a link pivotally mounted at its lower end 110 within said compartment and adapted to swing to both sides of its pivotal connection, a folding table leaf one section of which is pivotally connected to the upper end of said link, and a stop secured to said folding leaf 115 between the joint of said leaf and the point of connection of the link to said leaf and adapted to engage said link to hold the leaf in the plane of the top of the table.

In testimony whereof I affix my signature. 120

PETER NYHOLM.
